Assignor to

The Lowell Manufacturing Company, the same piece.

Letters Patent No. 1,419,474, dated July 24, 1874.

Design for a Carpet Pattern.

The schedule referred to in these Letters Patent and making part of the same.

That where it may concern:

Be it known that I, Elmer J. Key, of Lowell, in the County of Middlesex and State of Massachusetts, have originated and designed a new pattern for carpets or other fabrics, of which the following is a full, clear and exact description reference being had to the accompanying drawings, making part of this specification.

A is one half of a large set figure having a border of scrolls resting on the dotted ground 1.

The ground 1, of which one half is shown in the drawings, is enclosed by the branches and leaves 2, 2.

B is one half of a small oblong set figure, which rests on the ground 3. Said ground is bordered by a double row of small blocks outside of which is a diamond frame a part of which is shown in the drawings. The branches and pointed leaves 4, 4, are tightly overlaid and enclose the diamond frame and double row of blocks before mentioned.

C and D are sides when matched form figure composed of a ground of parallel lines enclosed by small scrolls, said figure resting on the ground 5, 5, which is surrounded by irregular leaves and sprigs.

E is the centre of a large set figure the particular form of which is shown in the drawings.

In the four corners are fourths of figures similar to E in the centre, with the exception that their position in the design is at right angles with that of E.

Connecting figure E with the corner figures are bands of key work 6, 7, 8, 9.

The colors employed for the different portions of the design, may be varied to suit the taste and wish of the manufacturer.

Claim.

What I claim as my invention, and desire to secure by Letters Patent, is The Design or Pattern for carpet, or other fabrics, herein set forth.
